C. G. YOUNG.
SUPERSENSITIVE FUSE.
APPLICATION FILED JUNE 4, 1919.

Patented June 20, 1922.

Inventor

Cecil G. Young

UNITED STATES PATENT OFFICE.

CECIL G. YOUNG, OF THE UNITED STATES ARMY.

SUPERSENSITIVE FUSE.

1,420,300.

Specification of Letters Patent. Patented June 20, 1922.

Application filed June 4, 1919. Serial No. 301,794.

(FILED UNDER THE ACT OF MARCH 3, 1883, 22 STAT. L., 625.)

To all whom it may concern:

Be it known that I, CECIL G. YOUNG, Ordnance Department, United States Army, a citizen of the United States, stationed at

5 Frankford Arsenal, have invented an Improvement in Supersensitive Fuses, of which the following is a specification.

The invention described herein may be used by the Government, or any of its officers or employees in prosecution of work for the Government, or by any other person in the United States, without payment of any royalty thereon.

10 The subject of this invention is a supersensitive fuse for explosive projectiles and like structures.

15 The main object of the invention is the provision of a fuse which will be held in safe position during handling and while the projectile is in the bore of the gun, and which will be automatically released to armed position when the projectile leaves the bore.

20 The invention also contemplates the provision of means for equalizing air pressure to retain the firing pin from contact with the primer during the flight of the projectile and after release of the fuse to armed position.

25 30 A further object of the invention is the provision of a gas check.

Another object of the invention is the provision of novel means for connecting the parts of the fuse.

35 These objects are accomplished by providing a firing pin holder connected for rectilinear sliding movement to the head of the projectile and carrying the firing pin, the holder being retained in unarmed position 40 by suitable means, specifically, a split ring, which is automatically released during flight of the projectile, and providing a gas check in conjunction with the firing pin.

Practical embodiments of the invention 45 are shown in the accompanying drawing, where:

Fig. 1 is a longitudinal sectional view of an explosive bullet equipped with a fuse constructed in accordance with the invention;

Fig. 2 is a cross section on the line II-II of Fig. 1;

Fig. 3 is a fragmentary view in longitudinal section of a modification of the fuse; 55 and

Fig. 4 is a cross section taken on the line IV-IV of Fig. 3.

Referring to the drawings by numerals of reference:

A projectile or explosive bullet is shown 60 which comprises a hollow body or casing, 1, open at one end and in which is loaded an explosive charge, 2, the shell is counter-sunk at its forward or open end to form an annular shoulder upon which is seated a 65 washer, 3, and the counter-sunk portion is threaded for the reception of a primer casing 4, in which is loaded the primer, 5, held in place in the casing by seating upon the washer, 3. The primer casing, 4, is provided with an aperture, 4^a, to permit the firing pin to engage the primer.

An under cut portion, 6, is formed in the casing, 1, near its open end to provide an annular shoulder, 7, the purpose of which 75 will shortly appear. The end of the casing is angled off to form an outwardly diverging annular face, 8, upon which is seated a split ring, 9, the faces of which are inclined to conform to the inclination of the 80 face, 8.

A firing pin holder, 10, is reduced at its inner end and split to form flexible prongs, 11, provided with outwardly projecting flanges, 12, at their inner ends, which 85 prongs will contract as the holder is forced into place to permit the flanges, 12, to pass within the opening of the casing and spring into contact with the annular shoulder, 7, and thereby hold the firing pin holder 90 firmly in position. The holder, 10, is formed with a recess, 13, at its forward end and at the bottom of the recess is a spider, 14, tapped to receive the threaded end of a firing pin, 15, which is held in position to 95 enter the aperture, 4^a, and engage the primer, 5.

In practice the projectile is fired from a gun in the usual way and the force due to set-back will retain the ring, 9, in its normal 100 position until the shell has passed from the muzzle of the gun. As soon as the shell is free from the gun acceleration of the shell ceases and the force due to set-back is relieved thereby allowing centrifugal force due 105 to the rotation of the shell to act upon the split ring and open the same sufficiently to allow it to be thrown from the shell, thereby releasing the firing pin holder to armed position. After the split ring has been re- 110

removed from the shell and during the subsequent flight of the shell, air will enter the chamber formed at the forward end of the shell and behind the firing pin holder 5 through the recess in the spider, 14, and also through the space formerly occupied by the ring, 9, and the slots formed in the reduced portion, 11, of the holder. This air in the chamber will prevent rearward movement of 10 the holder, 10, due to head pressure as it will equalize the pressure upon the holder.

Upon impact the holder, 10, will be forced rearwardly causing the firing pin, 15, to come into violent engagement with the 15 primer, 5, thereby exploding said primer, which explosion will be communicated through the opening in the washer, 3, to the main charge, 2, in the shell, 1.

In the modified form shown in Figs. 3 20 and 4, the general structure is substantially the same as that heretofore described with the exception that the primer casing, 4', is 25 slideable into the shell, 1', and is held in place therein by a head, 16, the rear end of which head is reduced and threaded to engage with the forward or open end of shell, 1'.

The head, 16, is provided in its forward face with an annular groove, 17, which is 30 adapted to receive a tubular portion or guide, 11', which is formed integral with and extends rearwardly from the firing pin holder, 10'.

A split ring, 9', is interposed between 35 the beveled shoulder of the holder, 10', and a beveled edge of the head, 16, for the pur-

pose of normally retaining the holder in an armed position. The holder, 10', carries a firing pin, 15', which extends through an opening, 19, formed centrally of the head, 16, 40 and which projects into a chamber, 18, likewise formed in the head, 16. A collar, 15'', encircles the pin, 15', within the chamber, 18, and serves to hold the firing pin holder in position and also, when the fuse is fired, acts 45 as a check to prevent forward discharge of the gases due to explosion, thereby insuring the passage of exploded gases of the primer rearwardly to ignite the main charge, 2'.

Having fully described my invention, 50 what I claim as new and desire to secure by Letters Patent, is:—

1. A fuse, including a casing formed with a beveled end, a firing pin holder connected for rectilinear sliding movement to the 55 beveled end of the casing, a pin carried by the holder, a split ring seated on the beveled end and normally retaining the firing pin holder in unarmed position, and a primer in the casing and in position to be engaged 60 by the firing pin.

2. A fuse, including a casing formed with an inclined seat, a firing pin holder having a shoulder inclined to conform to the inclination of the seat connected for rectilinear 65 sliding movement to the casing, a split ring interposed between the holder and the casing and engaging the seat, said ring adapted to retain the pin holder in unarmed position, a pin carried by the holder, and a primer 70 adapted to be engaged by the pin.

CECIL G. YOUNG.
